SPRINKLER, INCLUDING COUPLING

Wray E. Dudley, Troy, Ohio, assignor to The Skinner Irrigation Company, Troy, Ohio, a corporation of Ohio

Application January 4, 1954, Serial No. 402,072

1 Claim. (Cl. 299—69)

This invention relates to sprinklers and more particularly to sprinklers for irrigating purposes which incorporate a rotary nozzle construction.

In sprinkler devices incorporating a rotary element, it is necessary to have a bearing for properly supporting the rotating parts with relation to the stationary elements, and this has presented certain difficulties heretofore from the standpoint of avoiding objectionable wear. A sprinkler is frequently subjected to extremes of temperature where it is allowed to stand without use for long periods in the sun, and is then supplied with water which is usually relatively cold with resulting alternate expansion and contraction of its parts. In addition, in many cases the water supplied may contain sand, or other finely divided abrasive material, and it is found that such abrasives have a serious effect upon the bearing surfaces, for example in the case of the bearing which is employed to take the thrust in a sprinkler incorporating an impact type nozzle structure where the nozzle is advanced or rotated with a step-by-step motion under the action of an impact device.

An additional hazard to which such sprinklers are often exposed in use is wind, and more especially to abrasive materials such as sand which are blown against the sprinkler by the wind. Difficult wind conditions of this nature are frequently encountered in areas where sprinklers are especially needed for irrigation purposes, as for example in portions of southwestern United States, and they can cause considerable damage to the sprinkler by abrasion unless adequate measures are taken for protection of the moving parts of the sprinkler.

It is accordingly a primary object of the present invention to provide a rotary sprinkler of improved and simplified construction which is capable of a long useful life under even the most severe adverse conditions outlined above without interference with its operation either by abrasive materials in the water supply or by wind and abrasive materials carried thereby across the area being irrigated by the sprinkler.

Another major object of the present invention is to provide a sprinkler assembly incorporating a sand-proof bearing and supporting unit which is of simple construction embodying a minimum of component parts and which utilizes the line pressure of the liquid flowing therethrough to increase its sealing pressure against access to the moving bearing parts by abrasive materials in the liquid.

It is also an object of the invention to provide a rotary sprinkler assembly in which the sprinkler body and its bearing and supporting unit are constructed for cooperative relation to shield as much as possible all of the moving bearing structure from abrasive materials carried by the wind.

Additional objects and advantages of the invention will be apparent from the following description, the accompanying drawings and the appended claim.

In the drawings—

Fig. 1 is a side elevational view, partly broken away,

2

showing a rotary sprinkler assembly constructed in accordance with the invention; and

Fig. 2 is a fragmentary section on a large scale taken on the line 2—2 of Fig. 1.

Referring to the drawings, which illustrate a preferred embodiment of the invention, the sprinkler assembly includes a rotary sprinkler body 10 constructed for mounting on the upper end of a suitable standard or supply pipe 11, and the sprinkler body incorporates a main nozzle 12 and a driving nozzle 13 arranged on opposite sides thereof. The driving nozzle 13 discharges a driving jet against a deflector device 14 carried by the impact arm 15 mounted for oscillating movement on the upper end of the body, and the impact arm in turn cooperates with an impact pad 16 on the portion of the body 10 carrying the nozzle 13 to cause step-by-step rotating movement of the sprinkler body with respect to the pipe 11. The speed of this movement is controlled by adjustment of the torsion spring 17, which is provided with an adjustable connection 18 with the sprinkler body, preferred results having been obtained with this mechanism constructed as disclosed in my copending application Serial No. 402,073, filed of even date herewith, now Patent No. 2,778,681. In addition to driving the sprinkler, the nozzle 13 also provides water for irrigation of the area immediately surrounding the sprinkler, while the water discharged by the main nozzle 12 falls in an annular area spaced around the sprinkler and the intermediate area watered by the driving jet.

This sprinkler assembly incorporates a special bearing and support constructed for maximum protection against damage by abrasive materials such as sand and the like which may be present in the water or may be carried by the wind. The main support is a tubular adapter 20 having a pipe thread 21 at its inlet end for direct mounting on the supply pipe 11. The outlet end of the adapter is similarly threaded to receive the lower end of a bearing member 22, which is preferably formed of bronze or like suitable bearing material and may advantageously have a hexagonal outer portion as shown to facilitate connection to the adapter, which is shown as having a similarly hexagonal portion.

A stem 25 of brass or other suitable material of low coefficient of friction is mounted for rotation and relative axial movement within the bearing member 22. The upper end of stem 25 extends into and is threaded or otherwise secured directly to the sprinkler body 10, and a thrust spring 26 surrounds the upper portion of stem 25 and rests on the upper end of the bearing member 22. As shown in Fig. 1, the lower end of the sprinkler body is formed with a skirt portion 27 proportioned to depend in telescoping relation over the spring 26 and the reduced upper end portion 28 of the bearing member to form a shield preventing abrasive materials from being blown by the wind against these moving parts, especially against the junction of the stem 25 with the upper end of the bearing member 22, as well as abrasive materials running down the sprinkler body, such for example, as soil splashed thereon by an adjacent sprinkler on an irrigation line.

The stem 25 is provided near its lower end with a circumferential collar portion 30, which may be integral therewith as shown, and this collar 30 forms the thrust surface for cooperation with the thrust bearing 32 formed by the lower end of the bearing member 22. A thrust washer or gasket 33 is mounted between these cooperating thrust surfaces as shown, and the thrust spring 26 supports the weight of the sprinkler body on the bearing member 22 with sufficient force to maintain the seal at the thrust washer 33 whether the sprinkler is operating or at rest. This spring also provides resistance to prevent the sprinkler from turning backwards under low

pressure conditions, such as during the gradual buildup of pressure in a field irrigation system, and in addition it maintains sufficient friction between the thrust washer and its mating surfaces to prevent too rapid rotation of the sprinkler. In operation, the line pressure also asserts an upward force on the sprinkler body increasing the thrust on the thrust washer 33, and the entire thrust of the rotative movement of the sprinkler head is sustained by these parts. It is therefore essential to continued smooth operation of the sprinkler that maximum protection be afforded against access to these thrust surfaces by any abrasive materials which may be present in the water supply.

In order to accomplish this result, the adapter 20 is formed with an internal annular seat 35 located intermediate its two ends, which may serve also as a seat to receive the lower surface of the shoulder 30 when the sprinkler is not in operation. The stem 25 includes a portion 36 of substantial length which projects beyond the shoulder 30 thereon into the interior of the adapter and below the seat 35. A sealing ring 40 is received on the under side of the seat 35 in sealing relation with the inner surface of the surrounding portion of the adapter and the outer surface of the projecting end portion 36 of stem 25. Highly satisfactory results have been obtained in operation with this ring 40 constructed as shown of resilient rubber material with a U-shaped section providing inner and outer annular lips 41 and 42 having a groove 44 therebetween and a substantially flat opposite surface 45 for firmly seated engagement on the seat 35.

The sealing ring 40 should be initially proportioned for definite sealing engagement with the opposed surfaces of the adapter 20 and the stem portion 36 as shown, and in operation the line pressure of the water supply will be applied in the groove 44 in such manner as to urge the lips 41 and 42 apart and thus into increased sealing engagement with the stem and the adapter. As the result, thoroughly effective sealing is provided against any possible access of the liquid and any abrasive materials therein to the upper portion of the adapter which encloses thrust bearing surfaces of the stem and the bearing member. At the same time, it will be seen that this bearing unit is of very simple construction and provides not only definite advantages of economy of manufacture, but also is easily maintained and serviced as may be required for replacement of the sealing ring or the thrust washer. This supporting unit thus cooperates with the sprinkler body as described to give positive assurance against interference with operation of the sprinkler by abrasive materials either in the water supply or being blown across the land and accordingly provides maximum assurance for the continued long operating life of the sprinkler.

While the device herein described constitutes a preferred embodiment of the invention, it is to be understood that the invention is not limited to this precise device, and that changes may be made therein without

departing from the scope of the invention which is defined in the appended claim.

What is claimed is:

In a rotating sprinkler having a rotating sprinkler body 5 for mounting on a water supply pipe, the combination of a tubular adapter having its inlet end constructed for attachment to said pipe, said adapter including an integral internal portion forming an annular seat intermediate the ends of said adapter, a bearing member secured 10 to the outlet end of said adapter, a hollow stem journaled in said bearing member to receive the liquid from said pipe, said stem having thereon a circumferential shoulder located within said adapter and on the outlet side of said seat therein, a thrust bearing on the inlet end of said bearing member for rotatable thrust engagement with said shoulder, said stem including an end portion projecting beyond said shoulder thereon into the interior of said adapter and beyond said seat, means for securing the outlet end of said stem to said sprinkler body, a sealing ring 15 of resilient material received on said seat between the inner surface of said adapter and the opposed outer surface of said projecting end portion of said stem, said ring being of generally U-shaped cross section providing inner and outer annular lips with a groove therebetween, 20 said sealing ring having its surface opposite said groove therein constructed for seating on the surface of said seat remote from said thrust bearing to maintain said ring spaced from said thrust bearing with said groove facing said inlet end of said adapter to cause the line pressure 25 to urge said lips into sealing engagement with said opposed surfaces of said adapter and said stem preventing access of said liquid to said thrust bearing while providing for relative axial movement of said stem and said adapter without affecting the sealing engagement of said 30 sealing ring therewith, and said opposed surfaces of said adapter and said stem being smoothly cylindrical for readily maintained sealing engagement with said lips.
